UNITED STATES PATENT OFFICE.

DAVID STOLL, OF NEW YORK, N. Y.

DESIGN FOR ENGRAVED SHEET METAL.

Application filed November 17, 1923. Serial No. 7,807. Term of patent 7 years.

To all whom it may concern:

Be it known that I, DAVID STOLL, a citizen of the United States, residing at the city of New York, county of Kings, and State of New York, have invented a new, original, and ornamental Design for Engraved Sheet Metal, of which the following is a specification, reference being had to the accompanying drawing, forming part thereof.

The figure is a plan view of an engraved sheet of metal showing my new design.

The surface ornamentation is engraved in the sheet by hand or by machinery, and the

outline is such that the sheet may be readily formed into an article of silver hollow ware by bringing the straight edges together. Said sheet is made and sold as an article of manufacture in itself, separate from and independent of any other article of which it may be afterwards used to form a part.

The design is symmetrical about the center line of the drawing.

I claim:

The ornamental design for engraved sheet metal, as shown and described.

DAVID STOLL.
